UNITED STATES PATENT OFFICE

126,091

DESIGN FOR A HAT ORNAMENT OR SIMILAR ARTICLE

Pauline Gaughran and Nathan Levine,
New York, N. Y.

Application October 19, 1940, Serial No. 95,942

Term of patent 3½ years

To all whom it may concern:

Be it known that we, Pauline Gaughran and Nathan Levine, both citizens of the United States of America, residing in the city of New York, county of New York, and State of New York, have invented a new, original, and ornamental Design for a Hat Ornament or Similar Article, of which the following is a specification, reference being had to the accompanying drawing, forming part thereof.

Fig. 1 is a plan view of a hat ornament or similar article showing our new design.

Fig. 2 is a rear view thereof.

We claim:

The ornamental design for a hat ornament or similar article, as shown.

PAULINE GAUGHAN,
NATHAN LEVINE,
